UNITED STATES PATENT OFFICE.

WILLIAM A. DOBSON, OF BRIDGEPORT, CONNECTICUT, ASSIGNEE TO UNDERWOOD
TYPEWRITER COMPANY, OF NEW YORK, N. Y., A CORPORATION OF DELAWARE.

TYPEWRITING MACHINE.

Application filed December 8, 1922. Serial No. 605,559.

The present invention relates to casings for typewriting machines, and more particularly to casings in which machines of the so-called portable class are carried from place to place by a handle on the casing.

Such casings are ordinarily in two parts, to wit, a part which comprises one wall of the casing and which serves as a base-board for the machine, and a cover-portion which defines the chamber within which the machine is set and which is placeable over the base-board and attachable thereto. Whereas the base-board may serve as the support for the machine in the operation thereof, it is often desirable to disconnect the machine from the board and employ another support therefor. To prevent injury to the machine, in the transportation thereof in the casing, it should, however, be securely affixed to the base-board when in the casing.

An object of the invention is the provision of means whereby, with expedition and accuracy, the machine may be centered upon, and securely attached to, the base-board; such means being of cheap and simple construction, and comprising a minimum of parts to be adjusted or manipulated.

Other features and advantages will hereinafter appear.

30 In the accompanying drawings,

Figure 1 is a view, in cross-section, substantially on the line 1—1 of Figure 2, through the assembled casing and machine.

Figure 2 is a top plan view on the line 35 2—2 of Figure 1.

The machine comprises a main frame 10 set within, and secured by screws 11 to, an outer ornamental frame 12. The main frame comprises side pieces 13, connected by front and rear cross-pieces 14 and 15. Mounted for up-and-down movement in the main frame, between case positions, is a shift-frame 16; the side plates 17 of which are connected at the rear by a cross-piece 18, and forward thereof by a cross-piece 19. The cross-pieces 18 and 19 have rails 20 and 21 formed, respectively, thereon, to serve as runways for the platen-carriage. The platen-carriage comprises side plates 22, in which the platen 23 is journaled, connected at the rear by a cross-piece 24 and at the lower portions thereof by a cross-piece 25. The rear cross-piece 24 carries a bracket 26, in which is journaled a roll 27 which rides on the rail 20. The lower cross-piece 25 is channelled at 28 to receive rollers 29, by

means of which the same is supported on the runway 21. A roller 30, carried by an arm 31 attached to the cross-piece 25, engages the under side of the rail 21 to hold the forward part of the carriage to the rail. A lip 32, on the bracket 26, underlies the rail 20 to hold the rear of the carriage to that rail. The carriage is provided with the usual paper-table and apron-piece 33 which extends from the upper rear portion of the carriage down around and to the front of the platen.

The lower edges of the plates 13 of the main frame have flanges 34 offset inward therefrom. Front and rear feet 35 and 36, respectively, are secured to each of the flanges 34. For securing the feet, the same have their under faces countersunk, as at 37, to receive the heads 38 of screws 39, which pass upward through the feet and thread into the flanges 34. The feet have heads or enlargements 40 at their lower extremities, defined by shoulders 45. These heads rest upon the base-board 46. Secured at their front and rear ends to the upper face of the base-board, by means of screws 47, one at each side of the base-board, in alignment with the feet of the typewriting machine, are anchor-plates 48. Between the lines 49 and 50 (see Figure 2), the anchor-plates lie flat against the base-board. Beyond the lines 49 and 50 (as shown in Figure 2), the anchor-plates are offset upward, as shown in Figure 1, to provide horizontal elevated portions 51 and 52, respectively, at the front and rear of the plates.

The rear portions of the plates are enlarged, as at 53, and these enlargements have openings 54 therethrough, of a size to receive the heads 40 of the rear feet of the machine. In positioning and securing the machine to the base-board, the machine is set flat on the base-board in such position that the heads 40 of the rear feet of the machine are within the openings 54 in the anchor-plates. The machine is then forced rearward on the base-board so as to cause the heads 40 of the rear feet to pass under the rear elevated portions 52 of the plates. In this operation, the narrower portions 55 of the rear feet are received in openings 56 in the elevated rear portions 52 of the plates; the openings 56 being extensions of the openings 54, constricted to prevent upward movement therethrough of the heads 40 of the feet when the machine shall have been thus thrust rearward. The shoulders or upward offsets 57, which define the rear edges of the

elevated plate-portions 52, may serve as stops to determine the extent of rearward movement of the machine on the base-board and to define the true centered position of the 5 machine.

When the machine has been placed and thrust rearward, as just described, certain screw-holes 58 in the flanges 34, near the forward ends of the latter, register with 10 certain other screw-holes 59 in the base-board. Blocks 60, having screw-passages therethrough, are set into openings 61 in the forward elevated portions 51 of the anchor-plates, and rest upon the base-board, as 15 shown in Figure 1, with the screw-passages therethrough in registration with the holes 58 and 59. The raised portions 51 have a rounded outer contour and are offset outwardly from the plane of aligned front and 20 rear feet so that the tangential planes of the raised portions and adjacent front feet tend to overlap. Screws 62 are then passed down through the flanges 34, through the blocks 60 and base-board 46, to be threaded 25 into and locked by nuts 63 set into countersinks 64 in the under face of the base-board. When the blocks 60 have thus been set in the openings 61 in the anchor-plates and secured 30 to the machine and to the base-board, the forward elevated and rounded portions 51 of the anchor-plates will prevent forward or sidewise movement of the machine to release the rear feet thereof from the rear elevated portions 52 of the anchor-plates; and 35 the screws 62 having been tightened, upward movement of the front part of the machine, sufficient to clear the blocks 60 from the elevated portions 51 of the anchor-plates, is prevented. The height of the 40 blocks 60 is such as substantially to fill the space between the upper face of the base-board and the lower faces of the flanges 34, and, therefore, the blocks cannot be cleared 45 of the anchor-plates by upward shift of the blocks on their retaining screws 62. The blocks 60, as well as the feet of the typewriter, may be of rubber.

It will be noted that one and the same 50 anchor-plate or piece comprises the means for holding both the rear and front feet of the machine at one side of the latter; and that such anchor-plate may consist of a single piece of sheet-metal formed in one or more stamping and bending operations.

Variations may be resorted to within the 55 scope of the invention, and portions of the improvements may be used without others.

Having thus described my invention, I 60 claim:

1. The combination with a typewriting machine having shouldered rear feet on the frame thereof, of a base-board for the machine, and means securing the machine in its rearmost position on the base-board, including anchor-plates permanently secured on

the board, one at each side of the same; said anchor-plates having apertures therethrough to receive the shoulders of the rear feet of the machine while resting upon the base-board, and beyond such apertures having portions turned up from the base-board 70 to permit the shoulders of the feet to pass thereunder when the machine is moved backwardly, said portions having slots forming constricted extensions of said apertures to receive the constricted portions of the feet above the shoulders of the latter, to hold the machine down onto the base-board, and means at the forward end of the machine for anchoring the machine on the 80 base-board against movement in any direction.

2. The combination with a typewriting machine having shouldered rear feet on the frame thereof, of a base-board for the machine, and means securing the machine in its rearmost position on the base-board, including anchor-plates permanently secured to the board, one at each side of the same; said anchor-plates having apertures therethrough to receive the shoulders of the rear feet of the machine, and beyond such apertures having portions which are turned up from the base-board to permit the shoulders of the feet to pass thereunder, and which have slots forming constricted extensions of said apertures to receive the constricted portions of the feet above the shoulders of the latter; and said anchor-plates at the forward part of the machine having apertures therethrough, blocks resting on the base-board in the apertures, and bolts passed through the frame-members of the machine-base-board and the blocks rigidly securing the machine to the blocks and to the base-board.

3. The combination with a typewriting machine having shouldered rear feet, of a baseboard for the machine, anchor-plates secured to the baseboard and having their rear ends shaped to indenture and be interlocked with the shoulders of the rear feet for preventing the rear feet from being lifted upwardly from the rear ends of the anchor-plates, means at the forward part of the machine interlocked with the anchor-plates for preventing movement of the machine along the baseboard with the rear feet and rear ends of the anchor-plates interlocked, as aforesaid, and means including 115 screws secured to the under side of the base board and passed through said board and machine fastening the board and machine together with the upper ends accessible for manipulation from above, preventing lifting of the forward part of the machine from the baseboard.

4. The combination with a typewriting machine having shouldered rear feet on the frame thereof, of a base-board for the ma- 130

chine, and means for securing the machine to the base-board, comprising anchor-plates permanently secured to the board and provided with apertures in their forward portions and their rear ends, provided with key-hole apertures, interlocked with the shoulders of the rear feet of the machine, to prevent lifting of the rear of the machine from the base-board, blocks placed on the base-board in said apertures in the forward portions of the anchor-plates, and means passed through said blocks and base-board and engaging the machine and base-board for securing the blocks to the machine and to the base-board.

base-board.

5. The combination with a typewriting machine having shouldered aligned front and rear feet on the frame thereof, of a base-board for the machine, and means for
20 securing the machine to the base-board, comprising anchor-plates permanently secured to the board and provided at their front and rear with apertures, and offset from the plane of the feet of the machine,
25 and interlocked with the shoulders of the rear feet of the machine, to prevent lifting of the rear of the machine from the base-board, blocks on the front portion of the machine placed on the base-board in apertures in the integral forward portions of the anchor-plates offset from the plane of
30 aligned front and rear feet, and means for securing the blocks to the machine and to the base-board.

35 6. The combination with a typewriting
machine having front and rear feet and
flanges provided with screw-holes, of a base-
board for the machine, provided with screw-
holes registering with the screw-holes in the
40 flanges, and means for positioning the ma-
chine upon and securing it to the base-board,
said means comprising anchor-plates, one at
each side of the machine, said anchor-plates
45 having means at their rear ends interlocked
with the rear feet when the machine is in its
rearmost position upon the base-board, abut-
ments engaged with the front feet of the
machine, and means for anchoring the ma-
chine to the base-board comprising a fas-
50 tening member, including a screw in said
screw-holes, directly connecting the ma-
chine-frame with the base-board, said fas-
tening member being accessible for manipu-
lation from above said flanges and the bot-
55 tom ends of the screw secured in a counter-
sink in the bottom of the base-board around
said screw-holes.

60 7. The combination with a typewriting
65 machine having pairs of front and rear feet
and flanges provided with screw-holes, of a
base-board for the machine provided with
screw-holes registering with the screw-holes
in the flanges of the machine, and means
for positioning the machine upon and se-
curing it to the base-board, said means com-

prising unitary anchor-plates, one at each side of the machine, said anchor-plates having means at their rear ends interlocked with the rear feet on sliding the machine backwardly upon the base-board, and abutment-portions adjacent the forward end of the machine engaged with the front feet of the machine, said abutment-portions being offset from the plane of aligned front and rear feet and more widely spaced from each other than said front feet, to restrain lateral and rearward movement of the machine, and means for anchoring the machine to the base-board at each side of the machine comprising fastening devices including screws extending through said screw-holes and abutment portions and directly connecting the machine with the base-board, said fastening devices being accessible from above said flanges and countersunk in the bottom of the base-board and presenting no evidence of their presence at the exterior of said base-board.

8. The combination with a typewriting machine having front and rear feet, said rear feet having enlarged lower portions, of a base-board for the machine, and means for securing the machine to the base-board, said means comprising an anchor-plate for each rear foot, said anchor-plate including a flat portion resting upon and directly secured to the base-board, said flat portion having an opening in which a rear foot is receivable while resting upon the base-board, and an upwardly-bent portion presenting an opening of lesser diameter than the opening in said flat portion, in which lesser-diameter opening a smaller-diameter portion of said foot is received in interlocking relationship as the machine is moved rearwardly on the base-board, whereby movement of the machine away from the base-board at the rear thereof is prevented, and means at the forward end of the machine for anchoring the machine against forward, upward or lateral movement, relative to the base-board, including fastening devices rigidly securing the frame of the machine to the base-board.

9. A quick-attachable typewriting machine equipment for a typewriting machine having front and rear feet, the combination of a base-board, and a pair of rigid anchor-plates secured on said base-board, one at each side, means at the rear of said anchor-plates interlocked with the rear feet of the typewriting machine when the machine is in its rearmost position on the base-board, and means adjacent the front of the machine rigidly securing the machine on the base-board, including abutment-portions offset from said anchor-plates, threaded nuts inserted in said base-board, said abutment-portions having openings in registration with said threaded nuts, and screw-threaded fastening devices accessible for manipulation from above rig- 115

130

idly securing the frame of the machine and said metal plates together.

10. In a typewriter-fastening equipment, for a typewriting machine having aligned front and rear feet, the combination of a base-board, and an elongated anchor-plate at each side of said base-board, said rear feet each having an enlarged and a reduced diameter portion, said anchor-plates having upwardly and forwardly projecting portions engageable with said reduced diameter foot-positions above the enlarged diameter portions thereof when the machine is moved to its rearmost position upon the base-board,

and outwardly directed forward abutment-¹⁵ portions engaged with the front feet of said typewriting machine, said abutment-portions having openings offset from the plane of aligned front and rear feet, spacing members received within said openings between the ²⁰ frame of the machine and said base-board, and screw-threaded fastening devices extending through a portion of said frame, through said spacing members and into said base-board to rigidly secure the machine in ²⁵ place.

WILLIAM A. DOBSON.
